UNITED STATES PATENT OFFICE.

GIOSUÉ D'ESPOSITO, OF PITTSBURG, PENNSYLVANIA, ASSIGNOR OF ONE-HALF TO STUART PATTERSON, OF PITTSBURG, PENNSYLVANIA.

THIRD-RAIL SYSTEM.

SPECIFICATION forming part of Letters Patent No. 779,150, dated January 3, 1905.

Application filed March 12, 1904. Serial No. 197,882.

To all whom it may concern:

Be it known that I, Giosué D'Esposito, a subject of the King of Italy, residing at Pittsburgh, in the county of Allegheny and State 5 of Pennsylvania, have invented certain new and useful Improvements in Third-Rail Systems, of which the following is a specification.

This invention relates to electric railways, and particularly to those designated as "third-rail systems."

An object of this invention is to produce novel means for guarding the charged rail in order that the electric charge carried by the rail will not endanger life, since contact with 15 said rail, except its under surface, is prevented.

Furthermore, an object of the invention is to provide novel means for retaining and supporting the rail in certain relation to a track along which the motor is carried.

20 Furthermore, an object of the invention is to provide means for permitting access to the charged rail from the top by the removal of the guard or cover.

Furthermore, an object of the invention is 25 to produce novel means for insulating and supporting the rail, whereby leakage of current is prevented at the point of engagement of the charged rail and its supporting member.

30 With the foregoing and other objects in view the invention consists in the details of construction and in the arrangement and combination of parts to be hereinafter more fully set forth and claimed.

35 In describing the invention in detail reference will be had to the accompanying drawings, forming part of the specification, wherein like characters denote corresponding parts in both views, in which—

40 Figure 1 illustrates a side elevation of the third rail and its support fixed in certain relation to the rail of a car-track. Fig. 2 is a sectional view on the line 2 2 of Fig. 1.

In the drawings, A indicates a track-rail, B 45 the cross-ties thereof, and C the spikes for attaching the rail to the cross-ties, which elements being of any ordinary construction and forming no part of the present invention need

not be described in detail. A bracket D has flanges d , which engage the upper and lower 50 surfaces of the cross-tie, and a bolt d' is run through the said cross-tie and bracket for binding the said bracket in place. From an inspection of the drawings it will be observed that by reason of the engagement of the flanges 55 d with the cross-tie a rigid joint is made between the said bracket and cross-tie. The upper end of the bracket is provided with a flange d^2 , to which a girder E is secured by the bolts F, it being understood that a plural- 60 ity of such brackets are employed along a track for the purpose of supporting the girder at predetermined points.

On the inner surface of the girder is secured a filling-block G, which is provided with bevelled edges g , embraced by an insulating-washer g' . The upper edge of each washer instead of lying in contact with the edge of the filling-block G is curved upwardly over the 65 said filling-block in order to prevent moisture or water from passing between said washer and the rail. A cap g'' is provided at the joint, which will further protect the joint from the access of moisture. From an inspection of the drawings it will be observed that 70 insulating parts may be readily removed, and, in fact, the whole joint is of such construction that the elements thereof are accessible from the side and from the top and bottom. The filling-block and girder have coinciding 75 apertures g^3 and e , respectively, which receive an insulating-collar H, surrounding a bolt I, which extends through the girder and filling-block.

A third rail L, having a head i' , web i^2 , and base i^3 , is bound against the washer on the filling-block by the bolt which passes through the web of the rail and through a second filling-block J and girder L'. A collar M is provided at each end of the bolt. 80 90

A cover O is hinged to one girder by the hinge O' and extends over the space between the two girders to protect the charged rail, which is supported in place in the manner stated.

95 In utilizing the charged rail the brush or

collector is made to contact with the under surface or base of the rail, though by inverting the rail the head may be used as a contacting surface for the brush or collector.

- 5 The construction, operation, and advantages will, it is thought, be understood from the foregoing description, it being noted that various changes may be made in the proportions and details of construction for successfully 10 carrying the invention into practice without departing from the scope thereof.

Having fully described the invention, what I claim as new, and desire to secure by Letters Patent, is—

- 15 1. In a third rail for motor-cars, suitable cross-ties, brackets having flanges embracing the cross-ties, a girder secured to the bracket, a filling-block secured to the girder, the said girder and filling-block having apertures, a 20 bolt run through the filling-block and girder, a second filling-block and girder through which the bolt extends, a rail clamped be-

tween the filling-blocks and suitable means for insulating the parts.

2. In a third rail for motor-cars, suitable 25 cross-ties, brackets having flanges embracing the cross-ties, a girder secured to the brackets, a filling-block secured to the girder, the said filling-block and girder having coinciding apertures, a binding-bolt run therethrough, 30 a second filling-block and girder supported by the bolt, insulating-washers of the facing edges of the filling-blocks, a rail having its web clamped between the edges of the filling-blocks and insulating-tubes embracing the 35 bolt, as and for the purpose described.

In testimony whereof I affix my signature, in the presence of two witnesses, this 10th day of March, 1904.

GIOSUÉ D'ESPOSITO.
